TELEVISION RECEIVERS

Richard Montmeat, Fayetteville, and Richard E. Lee, Cazenovia, N.Y., assignors to General Electric Company, a corporation of New York

Application December 29, 1958, Serial No. 53,957

Term of patent 14 years

We claim:

The ornamental design for a television receiver, as shown.
